TEXTILE MANUFACTURE

Edward J. Abbott, Wilton, N. H., assignor to
 Abbott Machine Company, Wilton, N. H., a
 corporation of New Hampshire

Application February 17, 1940, Serial No. 319,387

17 Claims. (CL 19—1)

This application is a continuation in part of application Serial No. 137,492, filed April 17, 1937, for Textile manufacture.

This invention relates to an art and apparatus for preparing textile fibers for spinning or twisting, and has for one of its principal objects to provide an improved art and apparatus wherein textile sliver is subjected to repeated drawing operations in a continuous manner. In a preferred form the invention provides for gilling a sliver, then subjecting the sliver to a dividing operation, overlapping the successively formed short lengths in parallel relation and then gilling this assemblage of overlapped lengths, repeating this sequence of operations any desired number of times.

In conventional types of gills, the sliver, in ribbon-like formation, is drawn out a considerable amount, and then, before any further gilling or drawing operation, is gathered together laterally into a narrow strip, usually having a certain twist or false twist, which is then wound into a ball or onto a spool or formed into a coil in a can.

The present invention aims to improve upon this prior procedure by providing for doffing the gilled ribbon-like sliver from one gill and automatically feeding the same material in ribbon-like form to another gill, so that the operation is continuous.

A further object of the invention is to provide for automatically reversing the direction of the fibers, end-for-end during the course of their transfer from one gilling and drawing operation to the next so that they pass through successive similar treatments in opposite directions.

As applied to the production of worsted yarns, the present invention is adapted to serve as a substitute for one or more carding operations, with a consequent large saving in time and in machinery cost. Moreover there is an improvement in the character of the finally produced sliver. An examination of worsted sliver produced by the present invention shows that it does not contain the knotted type of nib which is produced by a card. Such nibs as are found in the sliver are found to consist of very short fibers rolled into a ball. These are left intact by the gills and are easily combed out by the combing operation.

The invention is moreover applicable to the reduction of textile fibers or filaments of the so-called continuous or endless type, such as natural silk, artificial silks of various kinds, artificial wool, etc. to staple lengths in readiness for spin-

ning according to the usual cotton, woolen or worsted systems. In the application of the invention to this use, the fibers can readily be disposed in parallel relation by passing them through a simple reed or the like, and such a reed may be substituted for the initial gilling operation which the invention applies to wool fibers.

In relation to the treatment of continuous fibers, the invention aims to provide an improved method and means for dividing a ribbon-like formation of the fibers into short lengths and for assembling the short lengths and forming them into a sliver.

Other advantages and objects of the invention will be apparent from this specification and its drawings wherein the invention is explained by way of example.

In the drawings:

Fig. 1 is a diagrammatic side view of apparatus for practicing the invention;

Figs. 2 and 3 are respectively diagrammatic plan and side views of another form of apparatus according to the invention.

It will be understood that as applied to the manufacture of worsted yarn according to this invention the sliver may be subjected successively to for example eight successive gills and be automatically doffed from the various gills and automatically delivered to the next succeeding gill. For convenience of illustration, the invention is shown as employing only two gills in succession.

Referring to the drawings, the sliver S may come to the gilling apparatus from any suitable source of supply, as for example from balls, or as illustrated from a can 11. Entering the first gill, which is indicated generally at 12, the sliver passes through slow-moving rolls 13, 13 and thence into the intersecting fallers 14, 14 which move at a slightly greater speed than the rolls 13, 13. The sliver then passes between front rolls 15, 15 which run at about six times the surface speed of the rolls 13, 13 with the result that the sliver is drawn out into a thin sheet.

An apron 16, running in the direction of the arrow x and between the front draft rolls 15, 15 at substantially their surface speed, carries the drafted sliver forward to sliver-dividing mechanism. In its preferred form, the sliver-dividing mechanism includes a lower breaker roll 19 and an upper breaker roll 20, both rotating continuously at approximately ten times the surface speed of the front draft rolls 15, 15. The lower breaker roll 19 rotates about a stationary axis, and the upper breaker roll 20 is mounted on a

frame 21 which is pivotally mounted at 22 in such manner that a spring 23 normally holds the roll 20 out of contact with the lower roll 19. While the rolls 19 and 20 are thus separated the drafted sheet of sliver passes without interruption over the smooth surface of roll 19 and thence downwardly onto an inclined plate 25.

A continuously rotating cam 27 acts on the frame 21 to depress the frame periodically, bringing the roll 20 down so that it presses the sliver against the lower roll 19. These two fast-moving rolls then pull off a portion of sliver from six to twelve inches long from the forward end of the sliver sheet and then separate, the upper roll 20 rising to its upper position.

Upon the pulling apart of the sheet of sliver, the plate 25 which is pivoted at 29, is moved in the direction of the arrow y by a connecting rod 30 which is operated by an eccentric 31 rotating in synchronism with the cam 27. This swinging of the plate 25 carries the pulled-off portion of sliver over onto an inclined conveyor belt 33 which preferably runs at approximately the surface speed of the rear rolls 13, 13' and which delivers to the similar rear rolls 13', 13' of a second gill 12'. The relatively slow speed of the conveyor belt 33 as compared to the relatively high speed of the sliver as it approaches the dividing rolls 19, 20, causes the pulled-off pieces to be assembled so as to lie on the belt 33 in overlapped formation and to be fed into the second gill in a plurality of thicknesses, for example six or eight, this overlapping being sufficient to make the rate of feed of the second gill approximately the same as that of the first gill.

The oscillating plate 25 in addition to assembling the pieces of the sliver on the conveyor 33 also reverses these pieces end-for-end, thus reversing the directions of the fibers as completely as if the product of the first gill had been wound up and then fed from a wound ball or the like to the second gill.

In the second gill, in which the parts are indicated by the reference numerals applied to the similar parts of the first gill but with the addition of primes, the product of the overlapping and reversing operation is further gilled and drawn. From this gill, the sliver sheet may be passed to further sliver-dividing mechanism, further assembling mechanism and further gilling mechanism such as previously described. Since the principle of the repeated gilling, drawing, sliver-dividing and assembling operations will be apparent from the illustrated apparatus of Fig. 1, the sliver S emerging from the second gill is for simplicity of illustration shown as then gathered together by a trumpet guide 37 and wound by means of drive rolls 38, 39 into a suitable package 40.

In the apparatus and process above described, the fibers of the material S are disposed in approximately parallel relation in a ribbon-like formation in the first gill 12, and thus arranged are advanced in a path from the gill 12 to the rolls 19, 20. These rolls 19, 20 successively divide the ribbon-like formation into short approximately staple lengths which are then caused by the tilting element 25 to overlap on the conveyor 33 lengthwise in their direction of travel while the conveyor continuously advances at a slower velocity than that of the undivided ribbon-like formation. By means of the second gill these overlapped short lengths are formed into a sliver.

In dealing with fibers that are available in continuous lengths so that merely by passage through

a reed or the like they may be disposed in parallel relation, the initial gilling operation and the end-for-end reversal that in Fig. 1 follows the first gilling operation may be dispensed with. Thus in Figs. 2 and 3, the creel 50 or equivalent device supports a large number of masses of fibers Q which are drawn off and pass through a reed or other device 51 to dispose them in parallel relation and in the same plane to form a sheet or ribbon-like sliver R. This sheet of parallel closely-adjacent fibers is passed between a pair of rolls 52, 53, the latter roll constituting supporting and driving means for an endless conveyor belt 54 which also passes about a roll 55 spaced from the roll 53. This conveyor belt has an upper substantially horizontal run which receives the sheet of fibers delivered from between the rolls 52, 53 which conveys this sheet of fibers to a fixed ledger blade 56 (or chopping block) with which cooperates a vertically reciprocating cutter blade 57. This blade is reciprocated in any suitable manner and at such intervals of time with reference to the speed of movement of the rolls 52 and 53 as to chop off uniform lengths 60 from the advancing end of the sheet, each such length being that of the desired staple.

Beneath the chopping part 56 is arranged a roller about which passes an endless conveyor belt 61 having an inclined upper run which is driven in the direction indicated by the arrow in Fig. 3. This belt 61 is driven at a speed slightly less than that of the belt 54, so that as successive cut-off portions of the sheet or ribbon R drop upon its inclined upper run, they will be advanced with such speed as to overlap each other as shown, for example, at 60^a and 60^b. These overlapping cut-off portions of the ribbon, each consisting of a great number of parallel, closely adjacent and equal lengths of fiber, are advanced by the belt 61 to any suitable device, for example, to drafting means capable of drafting the fiber and delivering it in the form of rope-like sliver, but as here shown the device 62 to which the overlapped cut-off portions of ribbon are delivered is a gill comprising the rear rolls 63 and 64, the forward rolls 65 and 66, and the intervening fallers 67. Any suitable draft between the front and rear sets of rolls may be provided, the action of the gill assuring a thorough blending of the successive overlapping portions of the cut-off ribbon delivered by the belt 61. After emerging from between the rolls 65 and 66, the blended, overlapping, commingled, but still parallel lengths of fiber may be condensed and, after passing between suitable rollers 68, may be coiled in a can 69 or otherwise collected for further treatment.

In the apparatus just above described, since the fibers across the entire width of the sheet are cut along the same transverse line, it is necessary to employ some such arrangement equivalent to the belt 61 to ensure the proper overlap of fibers necessary to the formation of a continuous sliver.

I claim:

1. Textile apparatus comprising a gilling device, means operating on the product of the said gill to divide it generally transversely, means for turning the divided pieces end-for-end and for assembling them in longitudinally overlapping relation, and a second gilling device arranged to receive the overlapped divided portions.

2. Textile apparatus comprising two gilling devices, means operating continuously during the operation of the first gill to divide the gilled prod-

uct of the first gill generally transversely, and means for feeding to the second gill the said gilled and divided product with the fibers thereof reversed end-for-end from their relative positions in the first gilling device.

3. Process of preparing textile material for spinning or twisting, comprising subjecting the material to a series of gilling operations, and between successive gilling operations drawing the material out several times in length, dividing the material generally transversely and assembling the divided lengths in longitudinally overlapping relation.

4. Process of preparing textile material for spinning or twisting, comprising subjecting the material to a series of gilling operations, and between successive gilling operations drawing the material out several times in length, dividing the material generally transversely and assembling the divided lengths in longitudinally overlapping relation, the extent of elongation of the material and the extent of overlapping of the material being such that the rate of feed of the material to the successive gilling operations is approximately the same.

5. Process of preparing textile material for spinning or twisting, comprising subjecting the material to a series of gilling operations, and between successive gilling operations dividing the material generally transversely, turning the divided lengths end-for-end, and assembling the divided lengths in longitudinally overlapping relation.

6. Textile apparatus comprising a gilling device, rolls between which the gilled product passes, said rolls turning at faster speed than the speed of exit of the material from the gilling device and being normally separated sufficiently so that the material passes between the rolls without being gripped thereby, means for intermittently causing said rolls to approach and grip the material thereby dividing successive lengths from the material leaving the gilling device, means for assembling the divided lengths in longitudinally overlapped relation, and a second gilling device adapted to receive the overlapped lengths.

7. Textile apparatus comprising a gilling device, means for dividing generally transversely the material treated by the gilling device, an element adapted to receive the divided lengths of material, a conveyor running at a slower velocity than the undivided material coming from the gilling device, means for moving said element intermittently to deposit divided lengths successively on said conveyor, thereby to assemble the divided lengths in longitudinally overlapping relation, and a second gilling device adapted to receive the assembled material from the conveyor.

8. Textile apparatus comprising a gilling device, means for dividing generally transversely the material treated by the gilling device, a tilting element adapted to receive the divided lengths of material, a conveyor, and a second gilling device receiving its supply from the conveyor, and means for operating the tilting element to turn the successive divided lengths of material end-for-end and lay them on the conveyor.

9. In a process of producing sliver, the steps of disposing a plurality of fibers in approximately parallel relation in a ribbon-like formation, advancing the said ribbon-like formation along a predetermined path, successively dividing the said ribbon-like formation transversely into short lengths, overlapping the successively formed short lengths in parallel relation while con-

tinuously advancing the overlapped short lengths at a slower velocity than that of the undivided ribbon-like formation and forming the overlapped short lengths into a sliver.

5 10. In a process of producing sliver, the steps of disposing a plurality of fibers in approximately parallel relation in a ribbon-like formation, advancing the said ribbon-like formation along a predetermined path, successively dividing the said ribbon-like formation transversely into short lengths, overlapping the successively formed short lengths in parallel relation while continuously advancing the overlapped short lengths at a slower velocity than that of the undivided ribbon-like formation and gathering the overlapped short lengths into a continuous sliver.

15 11. In a process of producing sliver, the steps of disposing a plurality of fibers in approximately parallel relation in a ribbon-like formation, advancing the said ribbon-like formation along a predetermined path, successively dividing the said ribbon-like formation transversely into short lengths, overlapping the successively formed short lengths in parallel relation while continuously advancing the overlapped short lengths, the speed of advance of the overlapped short lengths being sufficiently slower than that of the undivided ribbon-like formation so that the overlapped formation of short lengths is materially thicker than the undivided ribbon-like formation and forming the overlapped short lengths into a sliver.

20 12. In a process of producing sliver, the steps of disposing a plurality of fibers in approximately parallel relation in a ribbon-like formation, advancing the said ribbon-like formation along a predetermined path, successively dividing the said ribbon-like formation transversely into short lengths of approximately staple lengths, overlapping the successively formed short lengths in parallel relation while continuously advancing the overlapped short lengths at a slower velocity than that of the undivided ribbon-like formation and forming the overlapped short lengths into a sliver.

25 13. Apparatus for producing sliver comprising means for disposing a plurality of fibers in substantially parallel relation and in substantially the same plane in a ribbon-like formation, means for advancing the said ribbon-like formation along a predetermined path, means for successively dividing the ribbon-like formation transversely into short lengths, conveyor means adapted to support and continuously advance the short lengths resulting from each successive operation of the dividing means, said conveyor means moving at a slower speed than the said ribbon-like formation whereby the successively produced short lengths overlap in the direction of their travel on the conveyor means, and means operative to receive the overlapped lengths and to form them into a sliver.

30 14. Apparatus for producing sliver comprising means for disposing a plurality of fibers in substantially parallel relation and in substantially the same plane in a ribbon-like formation, means for advancing the said ribbon-like formation along a predetermined path, means for successively dividing the ribbon-like formation transversely into short lengths of approximately staple lengths, conveyor means adapted to support and continuously advance the short lengths resulting from each successive operation of the dividing means, said conveyor means moving at a slower speed than the said ribbon-like formation whereby the successively produced short

lengths overlap in the direction of their travel on the conveyor means, and means operative to receive the overlapped lengths and form them into a sliver.

15. In the process of producing spun yarn from fiber of the continuous type, disposing a plurality of said fibers in substantially parallel relation to form a ribbon-like sliver, advancing the sliver along a predetermined path, severing the sliver by a transverse incision thereby to cut off short lengths from the advancing ends of each fiber, advancing said severed lengths continuously while maintaining their parallel relation but at a slower velocity than that of the unsevered sliver, thus to cause the advancing end of the latter to overlap said severed length, again severing the ribbon by a transverse incision, repeating the above steps, and gathering the overlapped short lengths to form a continuous sliver.

16. Apparatus for use in producing spun yarn from fibers of the continuous type comprising means for disposing a plurality of said fibers in substantially parallel relation and in substantially the same plane to form a ribbon-like sliver, means for advancing the sliver along a predetermined path, a cutter having its edge disposed transversely across the path of the sliver and normally supporting the sliver, said cutter being operative to cut off in succession short lengths from the advancing end of each fiber, conveyor

means operative to support and advance the short lengths resulting from each successive operation of the cutter, said conveyor means moving at a less speed than the advancing end of the sliver whereby said advancing end overtakes and overlaps each successive set of cuttings, and means operative to receive the overlapped sets of cuttings and to condense them to form a continuous sliver.

17. Apparatus for use in producing spun yarn from fibers of the continuous type comprising means for disposing a plurality of said fibers in substantially parallel relation and in substantially the same plane to form a ribbon-like sliver, means for advancing the sliver along a predetermined path, a reciprocatory cutter having its edge disposed transversely across the path of the sliver, said cutter being operative to cut off in succession short lengths from the advancing ends of each fiber, conveyor means operative to support and advance the short lengths resulting from each successive operation of the cutter, said conveyor means moving in the same direction but at a less speed than the speed of the advancing end of the sliver, gilling means operative to receive the overlapped sets of cuttings from the conveying means, and means operative to receive the material from the gilling mean and to condense it into a continuous sliver.

EDWARD J. ABBOTT.
